[57] CLAIM

The ornamental design for an occupancy sensor cover, as shown and described.

DESCRIPTION

FIG. 1 is a top perspective view of an occupancy sensor cover showing my new design;

FIG. 2 is a front elevational view thereof, with the rear being open and unornamented; and

FIG. 3 is an end elevational view thereof, with the opposite ends being similar except, for the ribs appearing on opposite corners.

FIG. 1

FIG. 2

FIG. 3
